SCREENING APPARATUS

Joseph Baxter, Jr., Franklin, Ohio, assignor to
The Black-Clawson Company, Hamilton, Ohio,
a corporation of Ohio

Application December 8, 1937, Serial No. 173,628

7 Claims. (Cl. 216—149)

This invention relates to screening apparatus. One object of the invention is the provision of a screening apparatus adapted to screen paper pulp and other fluid material, and which is so arranged as to be capable of screening comparatively large quantities of material in a structure which is of comparatively small size and in which an effective screening action is produced.

Another object of the invention is the provision of a screen of the character mentioned, in which the screen plates are so arranged as to be self-cleaning and so that they may be washed without shutting down or removing any parts.

Another object of the invention is the provision of a screening apparatus which produces cleaner stock by effectively screening the desired constituents while the heavier impurities are caused to travel so that they are kept from entering the perforations or slots in the screen plates.

Another object of the invention is the provision of a screen for paper pulp stock and the like in which a substantially vertical screen is located between outer and inner walls, the screen dividing the space between the walls into horizontally juxtaposed discharge and supply chambers for screened and unscreened material respectively.

Another object of the invention is the provision of a screening apparatus having a vibratable container wall and a fixed material retaining wall, with a substantially vertically extending screen arranged between these walls.

Another object of the invention is the provision of a screening apparatus of the character mentioned in which compressible or yielding means are provided at one side of the movable or vibratory wall, the screen plates being held against such means, in fixed position.

Another object of the invention is the provision of a screening apparatus of the character mentioned in which the inner container wall is vibrated in an oscillatory manner and with relation to a fixed annular screen.

Another object of the invention is the provision of a screening apparatus having inner and outer walls and a screen provided between the walls and extending substantially vertically, the construction being such that the fluid entering the supplying chamber of the screening apparatus gives a circulating or whirling action to the liquid on the supply side of the screen.

Another object of the invention is the provision of a screening apparatus of the character mentioned certain parts of which are relatively ad-

justable so that the inlet pipe and the discharge pipe for the unscreened and screened material may be relatively positioned at desired locations.

Other objects and advantages of the invention will be apparent from the following description, the appended claims and the accompanying drawings in which

Fig. 1 is a side elevation of a screening apparatus embodying the present invention;

Fig. 2 is a top plan view of the screening apparatus, a portion being shown in horizontal section;

Fig. 3 is a vertical section on the line 3—3 of Fig. 2;

Fig. 4 is a section on the line 4—4 of Fig. 3; 15

Fig. 5 is an enlarged sectional view on the line 5—5 of Fig. 3, showing the eccentric adjustment;

Fig. 6 is a section on the line 6—6 of Fig. 5; and

Fig. 7 is a fragmentary perspective view showing the arrangement of the motor support.

The screening apparatus herein shown is one adapted to screen paper pulp and the stuff supplied to paper machines for the removal of undesired impurities and for holding back stock pieces 25 that have not been reduced to the desired fineness. However it will be apparent that the apparatus may be used for screening other kinds of fluid material.

Referring more particularly to the drawings 30 by reference numerals, the screening apparatus, which is designated generally by the reference numeral 10, comprises a base member 11, having a chamber 12 for receiving the screened stock. At one side of the base member is a discharge 35 conduit 13 which communicates with the chamber 12. The base member 11 has an upstanding wall 14 which is preferably flanged as indicated at 14, and which supports an annular fluid retaining wall or drum 15 projecting upwardly 40 therefrom. The wall 15 may be made of sheet metal suitably formed to provide an outwardly extending flange 16 at its lower end which seats on the flange 14 of the base. The two flanges are provided with a number of equally distant holes 45 spaced annularly so that the wall 15 may be located on the base in any desired position, and secured thereto by means of the attaching bolts 17 which extend through the two flanges.

Within the wall 15 is an annular container 50 wall or drum 20, and provided between the walls 15 and 20 is a screen shown in the form of an annular series of vertically extending screen plates 21 arranged end to end, and dividing the space between the two walls 15 and 20 into an 55

outer receiving supply chamber 23 and an inner chamber 24 for the screened material. The material to be screened is supplied to the outer annular chamber 23 through a supply passage 26 which is preferably located about midway between the top and bottom of the wall 15, and which is arranged tangentially as shown in Fig. 2 so that the fluid entering the supply chamber 23, which extends continuously around the screen, is given a whirling rotation in the direction of the arrow indicated in Fig. 2. This fluid supply passage 26 may be coupled to suitable supply pipes, and in view of the fact that the wall 15 may be mounted in any desired position on the base member it will be apparent that the fluid supply passage 26 may be located in close proximity to the fluid discharge conduit 18, or may be located on the other side of the screen or in any other position as may be most desirable for any particular installation.

The wall 20 of the screening apparatus, which is preferably of sheet metal, is given an oscillatory motion in a horizontal direction so that every part of this wall travels in a curved or circular path. The eccentric moving means for the wall 20 will be later described. The screen plate itself, however, is stationary, the oscillatory movement of the movable wall 20 producing a rapid change in the pressure of the liquid in the chamber 24 and increasing the effectiveness of the screen because of the rapid in and out movement of the material passing through the screen plate.

Provided between the screen plates 21 and the inner movable wall 20 are a series of yielding or compressible partition members, preferably formed of rubber or the like, and serving to divide the chamber 24 into a series of segmental portions, the lower ends of which are all in communication with the base chamber 12. These rubber walls, as shown at 28 in Figs. 2, 3 and 4, extend vertically along the outer side of the wall 20 and their outer vertically extending portions are provided with opposed angularly related surfaces 29 against which the terminal ends of the screen plates rest, the ends of the screen plates being turned inwardly as indicated at 30 in Fig. 4. The screen plates, which are rigid metal members provided with slots or holes of the desired size from the bottom up to a level about 6 inches or so below the normal level of liquid in the chamber 23, are pressed against the surfaces 29 of the rubber walls by holding members generally designated 32 and arranged between the outer wall 15, the ends of the screen plates, and the rubber walls 28. A single holding means is preferably provided for the adjacent ends of each pair of screen plates. This holding means includes a vertically extending metal bar 33 having an inwardly extending tongue 34 which fits into a vertical groove 35 in the rubber wall 28. The bar 33 is provided with side inclined walls 36 which fit against the inturned ends 30 of the screen plates, and carried at the top and bottom of the bar 33 are wedge members 37 and 38 having wedge surfaces inclined downwardly and inwardly and cooperating with the inclined surfaces of fixed wedge blocks 39 and 40 respectively, arranged at the top and bottom of the wall 15 opposite the joint between adjacent screen plates. It will be understood that one of these locking devices is provided opposite the adjacent ends of each pair of screen plates, the construction of the drawings showing six such locking means and six screen plates,

with the discharge chamber 24 divided into six segmental portions.

The lower ends of the screen plates 21 fit down into a recess provided at the upper end of a wall 43 in the base member, the plates being held inwardly against the upstanding wall 46 thus provided, by means of the wedging holding members above described, suitable rubber strips being provided between the screen plates and the wall 46 and also below the lower ends of the screen plates 10 as indicated at 46 so as to prevent leakage around the lower ends of the screen plates from the supply chamber to the discharge chamber of the screening apparatus and insuring that all of the screened material will flow through the holes in 15 the screen.

The holding members 32, at the upper ends thereof, rotatably support hand wheels 41 which are internally threaded for engagement with threaded T-bolts which project upwardly from the wedge blocks 39 so that when a hand wheel 41 is turned and screwed down on its T-bolt, the bar 33 is forced downwardly and, by the wedging action produced, is also forced inwardly so as to hold the ends of screen plates 21 against the rubber walls 28. The hand wheel 41 thus forms a single operating means for securing or loosening each holding member. When the hand wheels 41 are turned so as to be free of the threaded T-bolts on the wedge blocks 39, the holding members can be withdrawn vertically, thus freeing the screen plates so that they may be freely withdrawn in an upward direction. Each screen plate may be separately withdrawn without disturbing the mounting of all of the screen plates.

The lower end of the inner wall 20 has an inwardly extending flange 48 below which is a metal filler ring 47. Below the filler ring 47 is a rubber ring 49 of substantial thickness. This ring of rubber is bonded to upper and lower thin metal disks 50 and this composite member is supported on a horizontal flange 51 extending from the base member as shown in Fig. 3, and the upper and lower metal disks are secured as by means of bolts 54 and 55 to the flange 48 and the flange 51 respectively. The wall 20 is thus so mounted on the base member as to be capable of a horizontal movement in an eccentric path, the support of the movable wall, however, being such as to prevent leakage between it and the base member. With 50 a rubber ring of yielding rubber or the like, a total in and out movement of the order of about $\frac{1}{2}$ inch may be given to the wall 20.

The lower ends of all of the segmental portions of the discharge chamber 24 communicate 55 with the chamber 12 in the base, as previously mentioned, so that the screened stock which is passed horizontally through the screen plates can be taken off through a common discharge conduit 18 at the bottom of the apparatus. As the compressible or rubber walls 28 subdivide the discharge chamber 24 into a series of portions which communicate only at their lower ends with the common base chamber 12, it will be apparent that a vibratory movement imparted to the inner wall 20 will alternately exert compression and suction effects on the material in the discharge chamber 24 to increase the effectiveness of the screening action, it being understood that the stock to be screened is supplied to the chamber 23 to a 70 height near the top of that chamber, and that the flow through the discharge conduit 18 is so controlled that the fluid on the discharge side of the screen plates is only a little below the level of the fluid on the supply side. It will also be apparent 75

that as the movable wall 20 is oscillated, it will act on all of the screen plates in the same manner so that an even screening action is produced at all portions of the screening surface. Furthermore the compression of the rubber walls 28 produced by an outward movement of the inner wall 20 at any location produces an increase in the width or thickness of these walls 28, augmenting the compressive action of the movable wall 20 in changing the pressure on the discharge side of the screen plates.

The height of the material in the outlet chamber may be controlled by suitable means such as a vertically movable valve member 58 provided in the discharge pipe or conduit as shown in Fig. 3 by means of which the level of material being screened may be raised or lowered to submerge all or any part of the screen plates. As the outlet for the material is considerably above the level 20 of the lowest point in the supply chamber 23 there is a welling up effect on the stock and a smooth flow takes place through the screen and through the discharge conduit.

The space 57 provided between the upwardly extending walls 13 and 43 of the base member extends annularly below the supply chamber 23 of the screening apparatus, and is in free communication with that chamber and forms a sediment collecting space in which sand and other heavy impurities in the paper stock are retained, and from which these heavy settled impurities may be withdrawn continuously or periodically. To provide for the withdrawal of this collected matter, the base member 12 is provided with an outlet pipe 56 as shown in Figs. 1 and 2, this pipe being adapted for connection with a suitable valved discharge pipe extending to any desired point of disposal. The heavy impurities will readily settle down into the retaining space 57, and in view of the tangential direction in which the stock flows into the supply chamber 23, the whirling mass of stock not only keeps the outer surface of screen plates washed clear of any collection of pulp fibers, but also, by the centrifugal action of the whirling mass, throws the heavy impurities outwardly so that they travel along the inner surface of the wall 15 and are kept away from any rubbing action which would wear away the screen plates themselves.

The operating means by which the inner drum of the screening apparatus is vibrated is adapted to give a rapid vibratory movement in an eccentric path and in horizontal direction. The speed of vibration may be of the order of several hundred complete oscillatory cycles per minute, and since there is no instantaneous reversal of movement of any large mass, the speed of movement may be up to seven hundred oscillatory cycles per minute, or even more than that. This vibratory movement of the inner wall or drum 20 is obtained from a rotatable motor driven shaft 60 which is supported preferably by means of antifriction bearings 61 and 62 held respectively in an upwardly extending motor supporting standard 63 having three spaced feet, and in a pedestal portion 64 which extends upwardly from the base member 11 with the movable wall 20. The pedestal portion 64 has three spaced segmental portions on which the three feet of the standard 63 are supported.

The upper end of the shaft 60 extends into a pocket 68 and is connected by means of a flexible coupling 67 to the lower end of a shaft 68 which is rotated preferably at a speed of

several hundred R. P. M. from the electric motor 69, a gear reduction 70 being provided between the motor shaft and the shaft portion 68 so that the motor may operate at an efficient speed. The motor and the gear reduction are 5 preferably arranged as a unit, removably supported on the top of the supporting standard 63. When the motor and the gear reduction are removed, after loosening the hold-down bolts, not illustrated, the connection between either 10 the shaft 60 or shaft 68 and the flexible coupling permits separation of those parts. The motor supporting standard 63 is also removably attached, by suitable hold-down bolts, to the top of the pedestal portion 64, and when the 15 supporting standard 63 is withdrawn in an upward direction, the shaft and its bearings are pulled along with it, providing access to the space 71 in which the driven member of the eccentric drive is retained.

Fixed on the shaft 60 is an eccentric 73 having a circular eccentric surface 74. This eccentric, as shown in Figs. 5 and 6, is preferably so arranged that the amount of eccentricity may be adjusted to provide for adjustment of the amplitude of movement of the inner wall 20 of the screening apparatus. The eccentric member 73 is therefore provided with a tapered surface 76, of circular cross-section, which fits on the correspondingly shaped portion 77 provided eccentrically on the shaft 60, the tapered surface 76 being eccentric with respect to the surface 74. At the opposite end of the eccentric member 73 is a ringlike portion 78, having fixed therein a plurality of keys or teeth 79. These teeth 35 79 which are inclined with respect to the axis of the shaft 60, may be engaged in any of a plurality of grooves or sockets 80 provided in a grooved portion 81 on the shaft. The grooves or sockets in this portion 81 are arranged annularly 40 about a center which corresponds to the center of the eccentric portion 77 of the shaft. The eccentric member 73 may be relatively moved to the left as viewed in Fig. 5, disconnecting the eccentric surface 76 from the eccentric portion 45 77 of the shaft and disengaging the teeth 79 in order that the eccentric member may be rotatably adjusted on the shaft and then moved endwise to the position shown in Fig. 5. The eccentricity of the surface 74 can thus be varied. 50 The eccentric member 73 is held in any position of adjustment by a lock nut 82, see Fig. 3.

The outer surface 85 of the ring-like member is concentric with the surface 74 of the eccentric member, surface 85 having a small clearance within plate 92 of a spider 86 which includes a plurality of arms, preferably of steel plate, the outer ends of which are welded or otherwise secured to the inner surface of the wall 20. The plate 92 is provided with three 60 segmental openings of slightly larger size than the three segmental portion of the motor supporting pedestal 64, through which these portions of the pedestal extend. The eccentric surface 74 carries the inner race 88 of a ball bearing, the outer race 89 of which is carried in a cage 91 which is held within ring 90 which is welded or otherwise fixed to the plate 92 of the spider 86. The cage 91 is removable from the ring 90 when withdrawal of the shaft 60 is 70 desired. It must be apparent that as the shaft 60 is rotated, the entire spider is moved eccentrically with respect to the axis of shaft 60, and every part of the inner drum 20 is given a vibratory movement in a horizontal direction.

The cage 91 is preferably a closed chamber containing a suitable lubricant. This lubricant flows down to it from the upper bearing 61 and is conducted through a suitable conduit down to the lower bearing 62. After passing through bearing 62 the lubricant moves downwardly and meets a lower flinger ring 94 which operates in a small closed pump chamber 95, the action of the flinger ring increasing the pressure of the lubricant in the chamber 95 and forcing the lubricant up through a central passage 96 in the shaft to a discharge opening 97 which leads out into the cage of the upper bearing 61. It is thus apparent that the lubricant may thus be continuously circulated through the bearings due to the action of the flinger ring 94 and the cascade construction mentioned.

The lighter impurities that float on the top of the material in the supply chamber 23 may be removed periodically through a skim pipe 100 which is provided in the outer wall 15 at a point near the upper level of the liquid in that chamber. This pipe is provided with an adjustable dam or valve 101 so arranged that normally no flow takes place past it. An adjustable hand wheel may be employed to raise or lower the dam 101 to control the discharge of the lighter material remaining on the surface of the material.

A suitable cleaning fluid may be supplied under pressure through a cleaning pipe 102, indicated in dotted lines in Fig. 3. When there is no material in the apparatus this cleaning pipe 102, which is preferably connected with a flexible hose so that it can be entirely removed, may be moved along the inside and the outside of the screen plates as the water or other cleaning agent flowing through the hose is discharged forcibly against the plates. However it is unnecessary that the apparatus cease operations during this cleaning process, for both sides of screen plates are freely accessible from the upper end of the apparatus during operation. And due to the vertical positioning of the screen plates it will be obvious that not only is there substantial freedom from the collection of slime on either side, but additionally the construction is such that no air binding of the screen plates can take place. And with a screening apparatus in which there is only a limited surface of the material being screened exposed to the air and with the elimination of any falling flow of the liquid when exposed to air, there is a reduced tendency for the stock being screened to take up any air or to create foam. The apparatus acts effectively as there is a gentle flow of stock through the screen, and as there is a comparatively short length for the stock to travel from any screened plate to the outlet passage 18.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. A screen of the character described comprising an annular stationary container wall and a movable container wall for retaining fluent material, a screen provided between said walls in spaced relation therewith and dividing the space between said walls into discharge and supply chambers for screened and unscreened material respectively, power means for continuously oscillating said movable wall, and a series of yielding

division walls extending from the movable container wall and connected to the screen.

2. A screen of the character described comprising an annular stationary container wall and a movable container wall for retaining fluent material, a screen provided between said walls in spaced relation therewith and dividing the space between said walls into discharge and supply chambers for screened and unscreened material respectively, means supporting said movable wall for eccentric movement, power means for continuously operating said movable wall on its eccentric support, and yielding division walls extending from the movable container wall to the screen and connected to both the screen and the movable container wall.

3. A screen of the character described comprising an outer annular stationary container wall and an inner movable container wall for retaining fluent material, a screen extending vertically between said walls in spaced relation therewith and dividing the space between said walls into discharge and supply chambers for screened and unscreened material respectively, power means for continuously oscillating said movable wall in a predetermined orbital movement, and a series of division walls formed of yielding material and extending from the movable container wall to the screen.

4. A screen of the character described comprising an annular stationary container wall and a movable container wall for retaining fluent material, a series of substantially vertical rigid screen plates fixed between said walls in spaced relation therewith and dividing the space between said walls into supply and discharge chambers, screen retaining members, one for the two adjacent ends of each pair of screen plates, connecting said plates to the stationary container wall, a series of yielding division walls extending from the yieldable container wall to the screen, and power means for continuously oscillating said movable wall.

5. A screen of the character described comprising an annular stationary container wall and an inner movable container wall for retaining fluent material, a screen extending vertically between said walls in spaced relation therewith and dividing the space between said walls into discharge and supply chambers for screened and unscreened material respectively, power means for continuous oscillating said movable wall, a series of yielding division walls extending from the movable container wall and connected to the screen, and an inlet passage extending tangentially with respect to said stationary wall to provide for rotational flow of the material supplied to the supply chamber.

6. A screen of the character described comprising an annular stationary container wall and a movable container wall for retaining fluent material, a series of substantially vertical rigid screen plates provided between said walls in spaced relation therewith and dividing the space between said walls into discharge and supply chambers for screened and unscreened material respectively, wedge members corresponding in number to the number of screen plates, each wedge member holding adjacent ends of two adjacent plates to the stationary wall, power means for continuously oscillating said movable wall, and yielding division walls extending from the movable container wall to the screen.

7. A screen of the character described comprising an annular stationary container wall and a

movable container wall for retaining fluent material, a screen extending vertically between said walls in spaced relation therewith and dividing the space between said walls into discharge and supply chambers for screened and unscreened material respectively, power means for continu-

ously oscillating said movable wall in a circular orbit, and a series of rubber division walls connected to the screen and extending to the movable container wall.

JOSEPH BAXTER, JR. 5
